How & Reicks
Stove Design

Patented 25 Nov. 1857

Ms. 426

Ezra Ripley & N.S. Bedder; of Troy, N.Y.

assignors to

Low & Hicks, of same place

Letters Patent, No. 426, Dated, Nov. 25, 1851.

The schedule referred to in these Letters Patent & making part of the same.

To all to whom these presents shall come:

Be it known that we,

Ezra Ripley & N.S. Bedder of Troy, in the county of Rensselaer, and state of New York, have invented or produced a new design of parlor ^{Stove}, which we call the "revere air tight" & we do hereby declare that the following is a full & exact description of the same, reference being had to the annexed drawing making a part of this specification, which is a perspective view of the stove.

The design of our stove consists of gothic arches formed by mouldings a, b, c, &c, and groups of diamond shaped ornaments d, e, f, g, h, and other ornaments on the top & bottom plates completing the configuration of style throughout in mouldings ornaments, legs & urn.

(What we claim & desire to secure by letters patent

is the design & configuration of a parlour stove, substantially the same as herein described & represented, in the annexed drawing.
